HANDLE FOR A CONTAINER

Richard C. Rheinhart, North Aurora, Ill., assignor to American Can Company, New York, N.Y.

Filed Mar. 25, 1970, Ser. No. 22,057

Term of patent 14 years

Int. Cl. D9—99; D8—03
U.S. Cl. D9—291

FIG. 1

FIG. 2

FIG. 3

FIG. 5

FIG. 4

FIG. 1 is a perspective view of a handle for a container showing my new design;

FIG. 2 is a side elevation view thereof;

FIG. 3 is a front elevation view thereof;

FIG. 4 is a bottom plan view thereof;

FIG. 5 is a sectional view taken along the line 5—5 of FIG. 1.

I claim:

The ornamental design for a handle for a container, substantially as shown.
